UNITED STATES PATENT OFFICE

165,343

LAMP

Thomas Raichel, Chicago, Ill., assignor to Deena Products Co., Chicago, Ill., a corporation of Illinois

Application June 15, 1951, Serial No. 15,545

Term of patent 7 years

(Cl. D48—20)

To all whom it may concern:

Be it known that I, Thomas Raichel, a citizen of the United States, and resident of Chicago, in the county of Cook and State of Illinois, have invented a new, original, and ornamental Design for a Lamp, of which the following is a specification, reference being had to the accompanying drawing, forming a part thereof, in which:

Fig. 1 is a side elevational view of a lamp, showing my new design;

Fig. 2 is a top plan view thereof;

Fig. 3 is an end elevational view; and

Fig. 4 is an elevational view showing the end opposite Fig. 3.

I claim:

The ornamental design for a lamp, substantially as shown.

THOMAS RAICHEL.
